(57) **CLAIM**

I claim the ornamental design for a handle for a step, as shown and described herein.

DESCRIPTION

FIG. 1 is a left-front perspective view of the handle for a step from above.

FIG. 2 is a left-side view of the handle for a step.

FIG. 3 is a front view of the handle for a step.

FIG. 4 is a right-side view of the handle for a step.

FIG. 5 is a rear view of the handle for a step.

FIG. 6 is a top view of the handle for a step; and,

FIG. 7 is a bottom view of the handle for a step. Broken lines are used in the drawings to illustrate features of the stool that form no part of the claimed design.
